UNITED STATES PATENT OFFICE.

BERNARD LIBERMAN, OF PHILADELPHIA, PENNSYLVANIA.

CIGAR-MAKER'S TABLE.

1,271,332.

Specification of Letters Patent.

Patented July 2, 1918.

Application filed April 14, 1916. Serial No. 91,019.

To all whom it may concern:

Be it known that I, BERNARD LIBERMAN, a citizen of the United States, residing at Philadelphia, in the county of Philadelphia, 5 State of Pennsylvania, have invented a new and useful Cigar-Maker's Table, of which the following is a specification.

The invention relates to improvements in a cigar maker's table. The object is to provide improved means for holding the wrapper during the operation of cutting by hand, that is with the knife adapted to travel over the leaf in cutting the wrapper therefrom, as distinguished from the wrapper per cutting die which is adapted to project through the suction platen. My improved means makes it possible to hold the leaf firmly and smoothly against the cutting block while the knife is moved in a slanting 10 position to cut the wrapper with a bevel edge. This makes it possible to roll the wrapper on the cigar with the bevel underneath so that none of the edge of the wrapper, which is frequently of different color 15 per cutting die which is adapted to project through the suction platen. My improved means makes it possible to hold the leaf firmly and smoothly against the cutting block while the knife is moved in a slanting 20 position to cut the wrapper with a bevel edge. This makes it possible to roll the wrapper on the cigar with the bevel underneath so that none of the edge of the wrapper, which is frequently of different color 25 from the surface of the wrapper, will be exposed and thus detract from the appearance of the cigar.

My invention comprises convenient means for associating the perforated cutting block 30 with the suction producing means, and for reversing the position of the block in order to secure the cutting of left hand and right hand wrappers as required.

The invention also comprises convenient 35 means for disposing of the butts cut from the cigars when cutting them to length, and also convenient means for holding paste and moistener containers in positions convenient to the operator, and means for shifting such 40 position to meet varying requirements.

Referring to the drawings which illustrate merely by way of example suitable embodiments of my invention—

Figure 1 is a plan view of a cigar wrapper cutting and rolling table showing my 45 invention.

Fig. 2 is a vertical section on line 2, 2 of Fig. 1.

Fig. 3 is a vertical section on line 3, 3 of 50 Fig. 1 on an enlarged scale.

Similar numerals refer to similar parts throughout the several views.

The cutting block 5 is made of a number of sections of wood clamped together by the

bolts 6, and nuts 7. These sections are of 55 substantial thickness, with the grain of the wood of the several sections preferably running parallel and at right angles to the plane of the cutting surface. The block is similar to the meat cleaver's block, with the 60 exception that a number of parallel channels 8 are drilled through the block and within a required area or contour and at right angles to the cutting surfaces of the block.

The top 9 of the table is provided with a 65 depressed portion 10 having a marginal shoulder 11 and a surrounding flange 12, for receiving and supporting the block 5. A gasket or packing 12, of rubber or other suitable substance is used to make a sub- 70 stantially air-tight relation between the block 5 and the depressed portion forming suction chamber 14. This chamber 14, is connected through tube 15 to a suitable suction creating means not shown. A valve or 75 gate 16 is provided to control the suction from chamber 14. This gate or valve 16 is operated in one direction by the pedal 17, connected through rod 18 and crank 19, and in the opposite direction by the spring 20. 80 When it is desired to increase the suction exerted upon the leaf or wrapper lying upon board 5, the pedal 17 is depressed, which opens valve 16. When it is desired to relieve or reduce the suction, pressure is withdrawn from pedal 17 and the spring 20 acts to close or nearly close the valve 16.

The area or contour of the area of the perforations or channel openings 8, is substantially that of the wrapper which is cut 90 from the leaf. As a matter of fact one longitudinal margin represents one longitudinal margin of the leaf and the other side the line upon which the wrapper is severed from the balance of the leaf. When the leaf 95 is held upon the block by the suction through the channel openings 8, and one margin of the leaf corresponding with one margin of the perforated area, the leaf is then cut with a beveled cut as and for the purpose above 100 indicated.

It will now be evident that the wrapper portion will still be held upon the perforated area of the cutting block by the suction exerted thereon, while the balance of 105 the leaf may be swept away or removed.

It will also be understood that the perforated area is of the substantial contour of

the wrapper, one end of which is the beginning end for rolling and wrapping and the other the finishing end.

It will be understood that this beginning end should be at the right hand or left hand side of the block, depending upon whether the operator is a right handed or left handed operator. As the channels 8 are all perfectly parallel and extend entirely through the thickness of the block, it follows that the contour of the perforated area on one side of the board will correspond to that on the other side, but reversed in direction, so it only remains to lift the block 5 from its seat within the flange 12 and turn it over and replace it within the flange to change it from a right hand to a left hand block and vice versa as the case may be.

It will also be noted that the area of perforations comprises only a small portion of the total area of the block 5, so that in case the operator desires to work without suction at all, the block may be turned over or around so that the area of perforations will be at the rear side of the block, leaving the forward or operating side of the block free from such perforations.

In tipping or finishing the tip or nose of the cigar, paste is used to hold the end of the wrapper in position, and this paste is usually contained in a receptacle conveniently located near the rolling table. When the paste becomes too thick or too dry, a method of moistening the same is frequently resorted to which is distinctly objectionable for hygienic reasons.

To obviate this objection I provide an additional receptacle for holding a sponge or other moistening device to which the operator may apply the hand or finger as occasion requires. For this purpose I provide the pivoted body 21 having two similar pockets 22 into which fit the receptacles or pots 23 and 24. In 23, for example, is the moistened sponge 25, and in pot 24 is the paste supply. This body 21 is secured to the top 9 of the table by the stud or screw 26, passing through an aperture 27 in body 21, centrally located as to one of the pockets 22, by this arrangement the body 21 may be swung into such position as shown in solid lines in Fig. 1, or in the position indicated by the dotted line on said figure, as shall prove the most convenient position for the particular operator working at the table.

When the cigar is wrapped and finished as to its end or nose, it is then cut to length by placing it in the trough 28 having the gage 29 properly positioned with respect to the graduations 30 and the knife 31 is then operated to cut the other end or butt from the cigar to give it a square end and uniform length.

Heretofore it has been customary to allow these cuttings to fall upon the surface of

table top 9 around the end of trough 28. This is objectionable for a number of reasons; the tobacco piles up and clutters the table, it is not kept clean as it should be for other uses. It is likely to blow about the table and from the table to the floor; all of which is unscientific and wasteful. This objection I obviate by providing an opening 32 through the table top 9 just beneath the knife 31 and the end of the trough 28. Through this opening all the tobacco cuttings will fall. Beneath the opening and beneath the table top 9, I secure a suitable receptacle 33, to receive the cuttings which fall through the opening 32. This bag or receptacle 33 is shown as supported by the hooks 34, removably connected with the eyes 35, which are secured to the underside of the table top 9, so that the receptacle may be removed from time to time in order to empty the same.

What I claim is:

1. In combination with suitable suction means, a wooden block for wrapper cutting and rolling, provided with a perforated area, one margin of which corresponds with the free edge of the leaf to be cut, and the other margin lies within the line of severance, said block providing an unbroken surface adjacent said last margin for receiving the cutting edge of a hand operated knife as the same is passed through the leaf into the surface of said block.

2. In combination with suction creating means, a cutting block having a perforated area in communication with the suction, said perforated area conforming to the shape of the wrapper, said block adapted to be turned over the underside becoming the cutting surface and vice versa, in order to change the perforated area from a right hand to a left hand block and vice versa.

3. A cigar maker's table having a chambered portion and suction producing means connected therewith, a surrounding recess with a gasket seated therein and a wooden cutting block having a portion of its upper and lower surface area perforated in required contour, and adapted to be fitted either side up in the recess and engaging the gasket.

4. A cigar maker's table having a chambered portion and suction producing means connected therewith, a surrounding recess with a gasket seated therein and a wooden cutting block having a portion of its upper and lower surface area perforated in required contour, and adapted to be removably fitted with either surface uppermost, in the recess and engaging the gasket.

5. In combination with a cigar maker's table, suction creating means and a cutting block having a perforated area lying entirely upon one side of the medial line of said block, means on said table for seating

the block arranged so that the block may be turned over or about so that the same may be positioned either with the perforated area near the operator or remote from the operator.

6. The combination with a cigar maker's table having a depressed portion surrounded by a flange, suction creating means connected with said recessed portion, and a cutting block removably seated within said

flanged portion and provided with an area of perforations located entirely upon one side of the medial line of said block whereby the block may be positioned with the perforations near to or remote from the operator.

BERNARD LIBERMAN.
